(57) **CLAIM**

The ornamental design for a hinge as shown and described.

DESCRIPTION

FIG. 1 is a perspective view of a hinge showing the new design disclosed herein;

FIG. 2 is a back view thereof;

FIG. 3 is a left side view thereof;

FIG. 4 is a right side view thereof; and,

FIG. 5 is a bottom left perspective view thereof.

The broken lines in the drawings depict portions of the hinge that form no part of the claimed design.
